UNITED STATES PATENT OFFICE.

RICHARD E. MALOY, OF BROOKLYN, NEW YORK.

APPARATUS FOR APPLYING GROMMETS.

Application filed December 21, 1921. Serial No. 524,036.

To all whom it may concern:

Be it known that I, RICHARD E. MALOY, a citizen of the United States, and a resident of the city of New York, borough of Brooklyn, in the county of Kings and State of New York, have invented a new and Improved Apparatus for Applying Grommets, of which the following is a full, clear, and exact description.

10 The present invention relates to an apparatus for effecting the application of grommets to the material and refers more particularly to the type of grommet disclosed in a co-pending application filed November 15 21, 1921, and bearing Serial No. 516,687.

Under the practice now generally employed grommets are applied by first cutting away a portion of the material to form the opening for the reception of the grommet body, said opening being of substantially the same diameter as the grommet body.

25 An object of the present invention is to provide a device in which this initial cutting away of the material is eliminated and in which means are provided for initially puncturing the material and gradually enlarging the puncture by rolling the edge of the material defining the opening to produce 30 a bead and at the same time rolling the grommet body over the bead to insure the proper gripping of the material thereby.

With the above recited and other objects in view, the invention resides in the novel 35 construction set forth in the following specification, particularly pointed out in the appended claims and illustrated in the accompanying drawings, it being understood that the right is reserved to embodiments other 40 than those actually illustrated herein to the full extent indicated by the general meaning of the terms in which the claims are expressed.

In the drawing—

45 Figure 1 is a fragmentary vertical sectional view of the apparatus illustrating the perforation of the material.

Fig. 2 is a similar view illustrating a further step, namely, the rolling of the material defining the grommet receiving opening and the expansion and rolling of the grommet body.

50 Fig. 3 is a similar view illustrating the clamping of the bead within the grommet.

55 Fig. 4 is a perspective view of a modified

form of the material perforating and bead forming element.

Fig. 5 is a similar view of a further modification.

Referring to the drawings by characters 60 of reference, 10 and 11 designate respectively the female and male die members, the latter consisting of a block having a circular recess 12 in its upper face provided with a concentric central bearing post 13 projecting above the upper surface of the block and having a reduced central trunnion 14. The material perforating and bead forming member 15 is of a diameter substantially 65 equal to the diameter of the bearing post 13 and is provided on its under side with a recess 16 for the reception of the trunnion 14, whereby the member 15 is detachably associated with the bearing post. The upper 70 extremity of the member 15 is tapered to 75 provide a pointed terminal 17. The female die member 10 is provided with a central opening 18 and a concentric circular recess 19 in its under surface. The female member 80 is further provided with an annular concentric collar 20 depending from the inner wall of the recess, said collar being provided with an upwardly and outwardly flared outer wall 21. The inner diameter of the collar and the size of the opening 18 are of substantially 85 the same size whereby the member 15 and bearing post 13 will be snugly received thereby when the members 10 and 11 are advanced toward each other.

In use and operation, the grommet comprising a substantially hyperboloidal body A and an outwardly flared annular flange B is arranged over and surrounding the bearing post 13 and member 15 of the die member 11 with the flange B resting within the 90 recess 12. The material C through which the grommet is to be inserted is then placed between the separated die members 10 and 11 and punctured by the pointed terminal 17 of the member 15, said puncture being 100 gradually enlarged by advancing the material toward its base thereby rolling the edge D of the material outwardly and advancing the same over the body A of the grommet. The die member 10 is then advanced toward the die member 11 until the lower edge of the collar 20 enters the upper 105 open end of the grommet bead A. Further continued movement of the member 10 toward the member 11 would cause the up- 110

wardly and outwardly flared outer wall of the collar to roll the upper edge of the grommet body outwardly until the same coacts with the circular recess 19. The final step 5 effects the simultaneous rolling of the material D into bead form and the body A of the grommet around the bead, thus formed to securely grip and maintain the grommet in place.

10 As illustrated in Figs. 1, 2 and 3 the material perforating and bead forming member 15 is provided with a plurality of angularly disposed faces 23 which produce a plurality of cutting edges 24 terminating in the pointed terminal 17. In lieu of this form, the member 15 may be provided with a conical upper extremity 25 as illustrated in Fig. 4, or with a plurality of concaved faces 26 terminating in upper cross cutting edges 27, as illustrated in Fig. 5. In the latter case a plurality of small cross cuts are initially produced in the material which are gradually formed into an opening by the rolling of the edge of the material upon itself to form a bead.

I claim:

1. An apparatus for effecting the insertion and application of a one-piece grommet to the material to which the same is applied comprising male and female die members, 30 means on the male member over which the grommet is arranged and seated, said means including a pointed extremity for initially puncturing the material, said extremity being of gradually increasing diameters toward the grommet seat portion for enlarging the puncture and rolling the edge of the material defining the puncture outward to 35 form a bead defining the opening for receiving the grommet body, and means on the female member adapted to engage within the grommet body upon advancement of the dies toward each other, said means being of

gradually increasing diameters for effecting the rolling of the body of the grommet over 45 said bead to embrace and clamp the same.

2. An apparatus for applying grommets embodying male and female die members, the former comprising a circular recess in its upper face having a concentric upstanding stem over which the grommet is arranged, the said stem being of gradually decreasing diameters and terminating in a pointed extremity at its upper end, whereby to effect an initial puncturing of the material, enlarging of the same by rolling the material defining the puncture outward to form a bead and an enlarged opening to receive the grommet body, the female member having a central opening, a recess at its 50 under side, and a depending sleeve flared outwardly and upwardly on its outer side for spreading and turning the upper end of the grommet body over the bead when the die members are advanced toward each other. 55

3. An apparatus for applying one-piece grommets to the material with which it is to be associated for forming an eyelet therein comprising male and female die members, 60 said male member having a projecting stem 70 over which the grommet is arranged, the said stem being pointed at its terminal and of gradually increasing diameters toward the base to afford means for initially puncturing the material, and subsequently enlarging the puncture and rolling the material outward to form a bead around an opening for the reception of the grommet body, the said female member having a central opening defined by a projection of gradually increasing diameters, which upon 65 movement of the die members toward each other extends over the stem and within the grommet to roll the same outwardly over the bead. 75

RICHARD E. MALOY.
